United States Patent Office.

JAMES H. MYERS, OF NEW YORK, N. Y., ASSIGNOR TO HIMSELF AND C. T. RICE, OF SAME PLACE.

Letters Patent No. 82,740, dated October 6, 1868.

IMPROVEMENT IN PATTERNS FOR CUTTING OUT SHIRTS.

The Schedule referred to in these Letters Patent and making part of the same.

TO ALL WHOM IT MAY CONCERN:

Be it known that I, JAMES H. MYERS, of the city, county, and State of New York, have invented a new and improved Pattern-Chart for Cutting Shirts; and I do hereby declare that the following is a full, clear, and exact description thereof, which will enable others skilled in the art to make and use the same, reference being had to the accompanying drawings, forming part of this specification.

Figure 1 is a view of the upper part of my half-shirt front diagram.

Figure 2 is a view of the upper part of the half-shirt back diagram.

Figure 3 is a view of the bosom diagram.

Figure 4 is a view of the yoke diagram.

Figure 5 is a view of half the neck-band diagram.

Figure 6 is a view of the half-sleeve diagram.

Similar letters of reference indicate corresponding parts.

My invention consists of a diagram made up of several parts or patterns, so shaped and graduated that the neck, chest, and waist-measurements of a person being determined, the proper shape of the different parts of a shirt is ascertained by the graduated boundary lines delineated upon said patterns.

All the patterns are arranged according to the general forms of persons, and the variations of each are produced with reference to the necessary variations of the others. Thus, for example, the length of the waist-line for half the front, shown in fig. 1, is, at its outer end, varied by graduations of half inches, each half inch indicating a difference of two inches in the circumference of the wearer at the waist, as the back, shown in fig. 2, is also graduated at the waist-line by graduations of half inches, which also indicate variations of two inches in the circumference. Each half-inch difference in half the front makes one inch in the whole front, and each half inch in half the back is one inch in the whole back, and thus the difference of two inches of the circumference is obtained. These marks are shown at *a* in fig. 1, and *b* in fig. 2.

When a person has a circumference at the waist of twenty-six inches, the line so marked on the patterns of the front and back, shows the outer lines requisite for shirts that will fit such person, and the upper end of such straight line, where it meets the arm-line of front (at *c*) or back, (at *d*), also indicates the requisite height of the shirt from the waist-line to the arm-pit.

The breast-measure is also indicated by the line *a b*, as shown, they being graduated according to general form. The shoulder-line, *e*, is determined from the circumference of the neck. It has been found that a person whose neck has a circumference of fifteen inches, measures from shoulder to shoulder eighteen inches, and in accordance to this the shoulder-line has been graduated, as shown in fig. 1, the figures 12, 13, 14, &c., thereon, indicating the length of shoulder-line at such a circumference of neck.

The arm-line, *f*, of front is drawn from the ascertained points of the shoulder-line to the outer line in the generally-adopted form. The upper line *g* of the shirt-back is formed from the yoke, fig. 4, on which the line *h* is determined according to the aforesaid rule, it being like half the distance from shoulder to shoulder, and the line *g* is four inches longer than *h*, to allow the gathering of the back part.

The arm-line *i* of the back is formed from the termination of the line *g* in the requisite manner.

The bosom-recess in the front piece, fig. 1, is also variable, according to fashion, desire, or size. The variations are indicated on the pattern by lines *A B C D*, which are half an inch apart at the sides, and one inch at the lower end of the bosom.

These same lines are also formed on the bosom-pattern *E*, which is shown in fig. 3, so that both patterns will agree.

The concave recess *l*, in the upper end of the bosom, is determined by the size of the neck. The neck-yoke, shown in fig. 4, is formed by the length of shoulder-line *e*, by that of half the shoulder-distance *h*, by a

suitable width, f , and by the neck-curve j . It will be seen that the lengths e , as well as h , are graduated, also that of the line j , the latter being controlled by the size of neck, as indicated.

The length of the collar-band, shown in fig. 5, is determined by the size of neck, and its height by fashion or desire.

The length of the upper sleeve-line k , fig. 6, is graduated according to breast-measure, corresponding to that of the added lines e and h . The graduations are marked on it, as is clearly shown in fig. 6:

From the above it will be seen that but the neck, breast, and waist-measures of a person of ordinary build are required to produce a shirt that will fit such person exactly, all the other measures, such as shoulder-length, arm-lines, &c., being computed from the three known measurements.

Having thus described my invention, what I claim as new, and desire to secure by Letters Patent, is—

The diagram for cutting shirts, consisting of the back, yoke, front, bosom, neck-band, and sleeve-patterns, of the configuration shown, having graduated measurements delineated thereon, substantially as shown, for the purpose specified.

JAMES H. MYERS.
